CLAIM

The ornamental design for a mini cone baking pan, as shown and described.

DESCRIPTION

FIG. 1 is a perspective view of a mini cone baking pan holding a cup cone typically used to serve candy.

FIG. 2 is a perspective view of the mini cup cone baking pan holding a rolled flour cone typically baked with ordeurves therein; and,

FIG. 3 is a bottom view of the baking pan shown in FIGS. 1 and 2.

The broken lines shown in the drawings are for illustrative purposes only and form no part of the claimed design.
